UNITED STATES PATENT OFFICE.

JOHN BERKEY AND WILLIAM F. KELLER, OF EASTON, PENNSYLVANIA.

COMBINED BURGLAR-ALARM AND DOOR-BELL.

SPECIFICATION forming part of Letters Patent No. 224,268, dated February 10, 1880.

Application filed August 27, 1879.

To all whom it may concern:

Be it known that we, JOHN BERKEY and WILLIAM F. KELLER, both of the borough of Easton, in the county of Northampton and State of Pennsylvania, have invented a new and useful Improvement in Burglar-Alarms and Door-Bells, of which the following is a specification.

The invention relates to burglar-alarms to be attached to doors or windows, and which may also be used as a door-bell.

The object of our invention is to improve that class of burglar-alarms which may be used as a door-bell, &c., and which is simple, efficient, and cheap, and may be attached to any door or window, no matter what the shape of the panels, molding, knob, and key-hole, that will strike when the knob is but slightly turned or the window opened but a short distance, and that is readily thrown in and out of gear.

The invention consists in certain novel combinations, as hereinafter set forth and claimed, of the following devices, viz: a gong to be struck by two hammers, one at each end of a continuous spring; a lever toothed at one end to operate the alarm, and having a notched opening at the other end to fit the hereinafter-described center-piece, whereby it is attached to the door-knob when used as a burglar-alarm on a door, and the lever operated by pins or other arrangement when used on a window, and by a knob or handle when used as a door-bell; a center-piece with a point fitting in the aforesaid opening in the lever, so constructed that the lever and gong may be set at any angle from the knob or handle, or the lever set at any angle with the gong; and, finally, the stop to throw the apparatus out of gear.

In the accompanying drawings, in which similar letters of reference indicate like parts, the apparatus being represented as attached to a door as a burglar-alarm, Figure 1 is a plan of our invention with the gong and knob removed. Fig. 2 is a sectional view on line *x y* of Fig. 1 with gong and knob on. Fig. 3 is an elevation, showing end of spring where it engages the teeth of the lever. Fig. 4 is a plan of the center-piece; and Fig. 5 shows the opening in the lever to receive the center-piece, from which drawings and the accompanying

description the other applications of our invention are readily understood.

E and F are the hammers attached to each end of the continuous spring G H I J K. N 55 P is the stop, turning on a pivot at O. L L' is the post supporting the gong. M is the hole through which the screw M' passes to attach the apparatus to the door. C and D are pins around which the spring passes. A 60 and B are pins against which the spring strikes when drawn back and released, making the blows of the hammers sharp and quick. S is the center-piece with an opening, R, through which the spindle R' of the knob T 65 passes. This center-piece has a point, *a*, which fits in a like opening in the lever Z, for the purpose of setting the device at any angle. Z is the lever, provided with teeth, as at Q, Q', Q'', and Q''', and an opening, S', 70 for the insertion of the center-piece S *a*, which opening has a notch, as at *a'*, *a''*, or *a'''*, for the adjustment of the device, as hereinafter described.

The operation of the apparatus is as follows: 75 When the door is closed the different parts are in the positions shown in Fig. 1. Then when the handle is turned—*e. g.*, to the left—the tooth Q'' engages the end of the spring G g and pushes it to G', when the spring is in 80 the position shown by the dotted lines G' I' J' K'; then the lever, passing still farther to the left, releases the spring, and it flies back, striking the pin B, which causes the hammer F to 85 strike the gong U V with a sudden sharp blow, and prevents it from resting against and stopping the vibrations of the gong after the blow is given. The knob or handle being turned still farther to the left, the tooth Q''' engages the spring, as before, and the same operation 90 is repeated. When the knob or handle is turned to the right a similar operation is performed on the other side of the gong, using the hammer E.

Doors and locks being of so many different 95 shapes respectively, and also with respect to each other, and windows being also of so many different patterns, if the device were constructed, as in Fig. 1, with the diagonal of the spindle R passing through the center of the 100 apparatus and without ready means of adjusting it to the door and lock or window, our in-

vention would be of little practical utility; but we obviate this difficulty by the construction of the center-piece S. When it is found necessary to set the apparatus at a different angle, all that need be done is to cut a notch with a three-cornered file at the proper place in the lever, as at a'' or a''' , to fit the point a of the center-piece.

The lever Z may be constructed with a different number of teeth, or with the same arranged in a different manner, or may be a whole circle instead of an arc; but we regard that shown in the drawings as the best form.

By pushing the stop N P to P' it thrusts the spring to one side, as shown by the dotted lines, and the teeth of the lever pass G' without engaging it, so that the door or window may be opened without giving an alarm. When attached to a window as a burglar-alarm the device may be placed on the frame of the window and the lever pivoted, as at Y, with pins on the sash, as at c and d , which strike the lever when the sash is raised or lowered, so as to cause the alarm to be struck, as above described; or it may be placed in other positions and operated by suitable devices.

What we claim is—

1. The combination of the continuous spring G H I J K, with a hammer at each end, the pins A, B, C, and D, the lever Z, with the teeth Q, Q', Q'', and Q''' and the notched opening S' a', the center-piece S, with its

point a , and the stop N P, substantially as and for the purposes above described. 35

2. In combination with the bell-striking mechanism of a burglar-alarm, the lever Z, with teeth Q, Q', Q'', and Q''' and notched opening S' a', for the adjustment of the apparatus, substantially as and for the purposes 40 above described.

3. The combination of the lever Z, with the teeth Q, Q', Q'', and Q''' and the notched opening S' a', and the center-piece S, with the point a , for the adjustment of the apparatus, 45 substantially as and for the purposes above described.

4. The combination of a continuous spring, G H I J K, with a hammer at each end, the lever Z, with the teeth Q, Q', Q'', and Q''' and 50 the notched opening S' a', and the center-piece S, with its point a , substantially as and for the purposes above described.

5. The combination of the continuous spring G H I J K, with a hammer at each end, the pins 55 A, B, C, and D, the lever Z, with the teeth Q, Q', Q'', and Q''' and the notched opening S' a', and the center-piece S, with its point a , substantially as and for the purposes above described.

JOHN BERKEY.
WM. F. KELLER.
